FENCE

Newton W. Richardson, Arcadia, Calif., assignor to Natural Gas Equipment Incorporated, Pasadena, Calif.,
a corporation of California

Filed May 12, 1961, Ser. No. 65,150

Term of patent 14 years

(Cl. D28—1)

FIG. 1 is a perspective view of a fence showing my new design;

FIG. 2 is a greatly enlarged sectional view taken on the line 2—2 of FIGURE 1; and,

I claim:

The ornamental design for a fence as shown.
